Primary Examiner — Mark A Goodwin*Assistant Examiner* — William B Melliar(74) *Attorney, Agent, or Firm* — Gearhart Law LLC;
David Postolski(57) **CLAIM**

I claim the ornamental design for a virtual reality flashlight, as shown and described.

DESCRIPTION

FIG. 1 is a front perspective view of a new ornamental design for a virtual reality flashlight.

FIG. 2 is a rear view of FIG. 1.

FIG. 3 is a bottom view of FIG. 1.

FIG. 4 is a front view of FIG. 1.

FIG. 5 is a left side view of FIG. 1.

FIG. 6 is a right-side view of FIG. 1; and,

FIG. 7 is a top view of FIG. 1.

The broken lines shown in the drawings depict portions of the virtual reality flashlight that form no part of the claimed design.
